UNITED STATES PATENT OFFICE

153,256

DESIGN FOR A MAN'S SHOE OR SIMILAR ARTICLE

Frank J. Braga, Hudson, Mass.

Application January 3, 1949, Serial No. 17

Term of patent 14 years

(Cl. D7—7)

To all whom it may concern:

Be it known that I, Frank J. Braga, a citizen of the United States of America, residing at Hudson, in the county of Middlesex and Commonwealth of Massachusetts, have invented a new, original, and ornamental Design for a Man's Shoe or Similar Article, of which the following is a specification, reference being had to the accompanying drawing, forming a part thereof.

Fig. 1 is a side elevation of a man's shoe embodying my new design;

Fig. 2 is a plan view of the shoe of Fig. 1; and
Fig. 3 is a front elevation of the shoe of Fig. 1.

I claim:

The ornamental design for a man's shoe or similar article, substantially as shown.

FRANK J. BRAGA.
